MEANS FOR LOCATING ENGINE TROUBLES

Earl L. Eaton, Lynn, Mass.

Application April 28, 1933, Serial No. 668,329

5 Claims. (Cl. 175—183)

This invention relates to a remote control for short circuiting spark plugs and means for locating troubles within internal combustion engines of the type equipped with spark plugs and used on automobiles, air-planes, tractors, marine engines, and the like.

The objects of the invention are to provide a trouble detector for internal combustion engines.

I accomplish the objects of my invention as shown in the accompanying drawings which form a part of this specification and in which similar letters of reference refer to similar parts throughout the various views.

Referring to the drawings, Figure 1 is descriptive of the device and shows the hook up. Figure 2 shows a sectional end view on the right-hand unit shown in Figure 3, and of that portion of my device which in use is normally placed beneath the hood of an automobile or elsewhere. Figure 3 shows a sectional side view of that portion of my device shown in Figure 2, two units only being shown, it being understood that any required number may be had. Figure 4 shows a partial plan view of the switch with which my device is equipped for the purposes of remote control. In use this switch is conveniently positioned at the steering wheel, or elsewhere. Figure 5 shows a sectional end view of said switch. Fig. 6 is a top plan view of the magnet.

Referring again to Figure 1, T shows the battery used for ignition. M shows a spark coil. N shows the distributor, and S the spark plugs. These parts are all common on internal combustion engines with which my device is intended for use. My device can be made for any number of cylinders, but for illustration I use only two of the complete circuits, showing one in open position and one in closed position, open position meaning that the device is not in working position, and closed position meaning that my device is in working position. The wire B¹ connects battery T with contact points B³ which are a part of the gang switch, this connection to the battery being connected on the same pole as the spark coil and distributor. I⁴, another contact point of the switch, is not in contact with B³ while in open position therefore no current can pass through the switch. I⁴ is connected by 50 means of the wire I³ to the coil I⁵ thus completing one side of the circuit to the coil I⁵. The other side of the circuit follows wire C¹ direct to the other side of the plurality of coils including the coil I⁵ and at a point designated by K¹, a wire C⁵ is connected to the wire C¹ and

wire C⁵ is connected on the other end to the permanent magnet G⁷ of the horse-shoe type and through the bearings to the swing arm G³ which has a tail piece G⁴ which is acted upon by an electromagnet, the operation of which is controlled by the switch I⁴ (detail of the electromagnet explained later). It will be understood that the permanent magnet G⁷ functions when the unit is in any position by returning the arm G³ and its tail piece G⁴ to its normal open position shown in the left unit of Figure 3 when the current is disconnected. The object of this arm G³ is explained in the next circuit which is similar to the one just explained, except that it is shown in closed position. When the device is in open position, the operation of the spark plugs S¹ is not interfered with. In the closed position wire B¹ connects the battery T with a contact point B³ as explained previously. In this circuit, the switch is closed and contact point I² is electrically connected to contact point B³, thus allowing the current to flow through wire I¹ to coil I, through the coil I to wire C¹, and back to the battery T. This causes the electromagnet to attract the tail piece G⁴ (see also Figure 3) and rotate the same in the bearings G⁵ and G⁶ towards the magnetized core H¹ (Figure 3). G³, being affixed to G⁴, Figures 1 and 3, and pivoted on the same arm, will swing up into contact with D¹, in the position as shown by G, see also Figures 1 and 3.

The operation is as follows: When the switch B³ and I² is open, current flows from the battery through the primary winding of the ignition coil M and back to the battery. Flow of current through the primary winding of the ignition coil M induces a high tension current in the secondary winding of the ignition coil M, which normally, or when the switches B³ I² and D¹ G³ are open, flows from the coil M through the distributor N, wires S³, spark plugs S, to ground on the engine and so back to the coil which is grounded. When a switch B¹ I² is closed and its coil I⁵ is energized to operate the armature G³ to close the electromagnet switch D¹ G³, the spark plug is shorted out and the high tension or spark plug current flows from the coil M through the distributor wires S³, wire F', switch D¹ G³, wire C⁵ wire C' back to coil M.

In the open position first above explained, it will be noted that arm G³ does not come in contact with contact point D¹ and therefore wire F' has no effect on the spark plugs S¹. All the circuits in my device act in a similar manner, and any number of spark plugs may be likewise shorted.

circuited by closing the switch which is on the line with said spark plugs. When dual ignition is used, contact with the two points D, Figure 2, is made simultaneously, so that an electrical connection may be made to each spark plug.

Figures 2, 3, 4, and 5, show more particularly the details of my device which embodies two parts, a switch box, and a unit box. The unit box which carries the main mechanism or parts 10 comprises the casing A, Figure 2, which has two exterior binding posts B and C, from which wires B¹ and C¹ connect my unit with the battery, wire B¹ corresponding to B¹ on the wiring diagram, which correspondence applies to wire C¹ and other parts similarly designated. From the binding post B a wire B² (not shown in the wiring diagram) conveys the current to plate B³, Figures 4 and 5, on the switch. The plate B³ acts as one of the contact points of my switch 15 and is so designed that one of a series of finger projections thereon projects under each button in the series of buttons. When the button is pressed, the respective finger thereunder contacts with another contact in the switch. The buttons designated as B⁴ and B⁵, Figure 5, operate the two sections shown. Button B⁴, shown in Figure 5, when pressed, forces a finger projection on plate B³ against a contact point I² which is part of plate I³, and said plate, through 20 wire I¹, is electrically connected to the coil I, Figures 1 and 2. This closes the circuit, allowing the current to flow through the coil I to the wire C³, Figures 1 and 2, which connects with the binding post C, through wire C⁴ in Figure 3, and thence back to the battery by means of wire C¹, Figures 1 and 2. The current passing 25 through the coil I causes the core H¹ which is within the insulated spool H to become magnetized, which attracts the tail piece G⁴ (see Figure 3) and forces the arm G, Figures 2 and 3, into contact with D. Wire C³, coming from the battery as heretofore explained, is always in contact with the artificial permanent magnet G⁷ within which is one of the pivot bearings for 30 G and G², and these parts being of electrically conductive materials, when arm G contacts with D, the electric current passes from D to the battery, through the arm G to the bearing block in G⁷, through the wire C³, back to the battery T as heretofore explained. The current travels 35 from the spark plugs S, through the wire F, Figures 1 and 2, to the binding post E¹, Figure 2, and D is the contact part of said binding post, Figures 1 and 2.

The coils I and I⁵ are optionally made with 40 an inner winding, designated by the character I⁹. The core H¹ comprises strips of wire, passing through the center of spool H. Any one of the coils I, with the corresponding core H¹, when 45 electrically connected with a source of energy, constitutes and functions as an electric magnet. G⁶ designates the second pivot point for the arm G. The arm G³ and tail piece G⁴, in Figure 3, are operated the same as arm G and finger G², in Figure 2. The switch button B⁵, Figure 5, is 50 shown not pressed in this case, and therefore the circuit is open. I⁴, Figures 1 and 5, show the contact point with which plate B³ would register if pressure was applied to the button B⁵. Contact point I⁴, Figures 1 and 5, is attached to a plate I¹, Figure 5, and is electrically connected to I⁵, Figures 1 and 3, by means of the wire I³, Figures 1 and 3. The other end of the coil is 55 connected to the binding post C, Figure 3, by

the wire C⁵, thence to the battery by wire C¹, Figures 1 and 2. D, Figures 1 and 3, shows the contact with which the arm G registers when current flows through the coil I. This coil I and wire C³, Figures 1 and 3, are electrically connected at K, Figures 1 and 2. C⁴, Figure 3, shows a wire which extends the full length of my unit, and with this wire, connections are made similar to that made by P, Figure 3. I⁶, Figure 3, shows a conduit used to shield the wires between switch and the other portion of my device. E and E², Figure 3, show binding posts to which the wires F and F¹, Figures 1 and 2, are connected, the said wires being also connected to the spark plugs. There are two contacts D, Figure 2, shown and two binding posts E² to allow connection to a cylinder in which dual ignition is used. When single ignition is used, only one of these binding posts and contact points are required. J shows the casing of my switch, Figures 4 and 5. The number of buttons on the switch should correspond to the number of the coils or pairs of binding posts designated by the characters E and E², Figure 3. L, in Figure 3, shows a hanger means by which my unit may be 60 suspended in convenient position while in use, a similar hanging means on the opposite end of my device is provided.

Having thus described my invention, I claim as new and desire to secure by Letters Patent of the United States of America:—

1. In a testing device, the combination with the spark plugs of an internal combustion engine, of a series of electromagnets including cores, permanent magnets mounted on the electromagnets, armatures carried by the permanent magnets, contacts associated with the plugs, and a switch device in circuit with the electromagnets for energizing and deenergizing the electromagnets to move the armatures into or out of engagement with said contacts.

2. In a testing device, the combination with the spark plugs of an internal combustion engine, of a series of electromagnets, permanent magnets connected with the electromagnets, connections between the electromagnets and plugs, armatures pivotally connected with the permanent magnets, and a switch device in circuit with the electromagnets and connections and operable to control the circuit to actuate the armatures to engage or disengage the contacts.

3. In a testing device, the combination with the spark plugs of an internal combustion engine, of electromagnets, permanent magnets mounted on the electromagnets, switch devices, contacts for the spark plugs, armatures pivotally connected to the permanent magnets, said armatures including tail pieces and arms, circuit wires connecting the electromagnets, and said switch devices to actuate the tail pieces of the armatures to move the arms thereof into or out of engagement with the contacts upon energizing or deenergizing the electromagnets through the medium of the switch device.

4. In a testing device, the combination with the spark plugs of an internal combustion engine, of a series of electromagnets, permanent magnets mounted on the electromagnets, armatures including tail pieces, means for pivotally connecting the tail pieces to the permanent magnets, arms carried by the tail pieces, contacts connected to the spark plugs, switch devices and current conductors connecting the electromagnets and switch devices, whereby when the electromagnets are energized the said arms will en-

gage said contacts and short circuit the spark plugs.

5. A short circuiting device for testing spark plugs of an internal combustion engine, comprising a plurality of electromagnets, permanent magnets mounted on the electromagnets, armatures pivotally mounted between the poles of the

permanent magnets, contacts adjacent the armatures, connections between said contacts and spark plugs, and electrical means in circuit with the electromagnets to energize or deenergize the electromagnets to move the armatures into or 80 out of engagement with said contacts.
